DESIGN FOR SAFETY GOGGLES

Hermon Moss and Jacob N. Rosenthal,
Los Angeles, Calif.

Application January 31, 1944, Serial No. 112,372

Term of patent 7 years

(Cl. D57—1)

To all whom it may concern:

Be it known that we, Hermon Moss and Jacob N. Rosenthal, citizens of the United States, residing at Los Angeles, in the county of Los Angeles and State of California, have jointly invented a new, original, and ornamental Design for Safety Goggles, of which the following is a specification, reference being had to the accompanying drawings forming part thereof.

Figure 1 is a front view of safety goggles, showing our design.

Figure 2 is a side view of the same;
Figure 3 is a perspective view of the same.
The head band shown in broken lines in Fig. 3 has been omitted from Figs. 1 and 2 for convenience of illustration.

We claim:

The ornamental design for safety goggles, as shown and described.

HERMON MOSS.
JACOB N. ROSENTHAL.
